UNITED STATES PATENT OFFICE

2,306,242

GAS BLAST ELECTRIC CIRCUIT BREAKER

Percy Bartlett, Springfield, Pa., assignor to General Electric Company, a corporation of New York

Application July 25, 1941, Serial No. 403,987

2 Claims. (Cl. 200—148)

My invention relates to gas blast electric circuit breakers, more particularly to those of the axial blast type wherein the interrupting arc is formed between separable contacts, at least one of which is hollow or tubular in form for receiving all, or a part of, the interrupting gas blast and has for its principal object the provision of an improved gas blast electric circuit breaker of the aforesaid type that is prompt, positive and efficient in its application of the interrupting gas blast to the point of arcing.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view in section of a gas blast circuit breaker of the axial blast type embodying my invention in the closed circuit position thereof, and Fig. 2 is a similar view showing the breaker in an initial stage of the opening operation.

The circuit breaker illustrated by way of example in Fig. 1 comprises relatively movable contact structure 1 and 2 in the form of tubular conductors separable to form an arc gap within an insulating housing 3 forming the arc chamber. The arc chamber is closed except for one or more gas blast supply conduits as indicated at 4 and the blast exhaust passages 1' and 2' formed respectively by tubular extensions of the contacts 1 and 2.

For the purpose of operating the contacts, the contact 1 is provided with a piston 5 operable in a cylinder-like portion of the casing 3 arranged to be acted upon by the blast pressure transmitted through the supply conduits 4. When the piston is raised it compresses biasing spring 6 and causes separation of the contacts. The contacts 1 and 2 in the arrangement shown in Fig. 1 are in abutting relation at the main current carrying contact surfaces indicated at 7 so as substantially to close the exhaust passages 1' and 2'. It will be apparent that other current carrying or primary contacts, such as laminated brush contacts can be provided if desired.

The arcing or secondary contacts connected to the contacts 1 and 2 comprise a pair of conducting extensions 8 and 9 which are suitably secured to the contacts 1 and 2 respectively. The arcing contact 8 consists of an extension of the tubular part of the contact 1 cut on a bias as indicated at 10 and provided on its inner 55

surface with an arcing tip 11 of suitable arc-resisting contact material, such as an alloy consisting of tungsten impregnated with copper. The coating arcing contact 9 consists of a conducting stud the tip of which may also consist of a similar arc-resisting alloy mounted centrally of the tubular contact 2 in any suitable manner as indicated at 12, the arrangement permitting free flow of exhaust gases through the contact 2.

In the closed circuit position of the breaker shown by Fig. 1, the abutting surfaces of the contacts 1 and 2 conduct the main part of the current through the breaker. In this position the arcing contacts 8 and 9 are also in "wiping" engagement. When the breaker is to be opened, as by admission of the blast gas to the conduits 4, and also, if desired, by simultaneous downward movement of the tubular contact 2, by suitable actuating means (not shown), the gas under pressure in the chamber 3 acts on the piston 5 to move the contact 1 upward away from the contact 2 so as to shunt the current through the arcing contacts 8 and 9.

Fig. 2 shows the arcing contacts still in engagement after initial separating movement of the contacts 1 and 2 at an intermediate point in the opening stroke. In this position, it will be noted that, although the contacts 8 and 9 are still in engagement, the blast exhaust passages 1' and 2' are in direct communication with the interior of the arc chamber by reason of the port at 10 that is opened upon initial movement of the contacts. This port admits the initial blast gas from the gas supply conduits 4 to the exhaust passages prior to actual separation of the arcing contact structure so that the blast is in practically full motion at the very inception of the interrupting arc.

Consequently, when arcing contacts 8 and 9 separate, the gas blast traversing the passages 1' and 2' is immediately effective by reason of its more intensive application to interrupt the arc at the first current zero. After separation of the arcing contacts 8 and 9 and extinction of the arc, a suitable isolating gap is formed between the contacts by continued separation thereof. It will be apparent, of course, that when the contact separating movement depends mainly on the piston operated contact 1, suitable disconnecting means connected in series with the breaker can be opened upon interruption of arcing and prior to return of the contact under bias of spring 6 to closed position.

It should be understood that my invention is not limited to specific details of construction

and arrangement thereof herein illustrated, and that changes and modifications may occur to one skilled in the art without departing from the spirit of my invention.

What I claim as new and desire to secure by Letters Patent of the United States is:

1. A fluid blast electric circuit breaker comprising an insulating arc chamber, relatively movable contact structures separable to form an arc gap in said chamber, means for directing an interrupting fluid under pressure to said chamber, and means responsive to fluid pressure in said chamber for causing separation of said contact structures, one of said contact structures being tubular to form an exhaust passage leading exteriorly of said chamber from the region of said arc gap and the other of said contact structures normally closing said passage in the closed circuit position, said contact structures normally overlapping in sliding engagement when closed and being arranged upon initial opening movement thereof to uncover by slide valve action a port in one of said contact structures for admitting fluid under pressure to said

passage prior to arcing caused by final separation of the overlapping parts of said contact structures.

2. A gas blast electric circuit breaker comprising an insulating arc chamber, relatively movable main contacts, one of which is tubular for defining an exhaust passage leading exteriorly of said chamber, separable to form an arc gap in said chamber, said passage being normally closed by said main contacts in the closed circuit position of said main contacts, means for directing an interrupting gas under pressure to said chamber, and means responsive to gas pressure in said chamber for causing separation of said contacts, said main contacts also having co-acting arcing portions arranged in overlapping telescopic relation with respect to said main contacts so as to remain in contact after initial separating movement of said main contacts, said main contacts thereupon opening said exhaust passage to initiate flow of the blast gas prior to separation of said arcing portions.

PERCY BARTLETT.
